UNITED STATES PATENT OFFICE.

EARL R. BROWN, OF GRENADA, MISSISSIPPI.

TRUCK OR WAGON BOX.

Application filed September 11, 1925. Serial No. 55,872.

This invention relates to truck or wagon boxes and has for an important object thereof the provision of a box which may be very cheaply and at the same time strongly constructed and which is capable of a wide range of use.

More specifically, it is the object of this invention to produce a wagon box capable of conversion from a box structure to a flat bed or a bed having inclined side walls, the structure being such that the flat bed provided is of much greater width than the ordinary flat bed of the wagon box and when the inclined side walls are provided, these are rigidly supported without the use of supports other than those built into and forming a portion of the construction of the wagon box.

These and other objects I attain by the construction shown in the accompanying drawings, wherein for the purpose of illustration is shown a preferred embodiment of my invention and wherein:

Figure 1 is a perspective view of a wagon or truck body constructed in accordance with my invention, the parts being shown in the position which they occupy when the device is in use as a box;

Figure 2 is a transverse sectional view therethrough, the parts in the position which they assume when the device is in use as a rack;

Figure 3 is a central longitudinal sectional view, the parts being broken away;

Figure 4 is an end elevation showing the device in use as a flat bed.

Referring now more particularly to the drawings, a flat bed is provided comprising longitudinally extending sills 10 upon which are arranged transversely extending joists 11 of a length greater than the width of the wagon box which is to be provided. The ends of the joists 11 are connected by longitudinally extending rails 12 seated upon the upper surfaces of the joists and between these rails a flooring 13 is mounted upon the joists. This flooring is of a width less than the distance between the rails so that a space 14 is left between the edges of the flooring and the rails at each side of the flooring. The joists adjacent the edges of the flooring have formed therethrough aligned openings 15 through which is directed a hinge bolt 16 which may consist of one of the usual wagon bolts, as illustrated.

Box sides 17 are provided, each consisting of a plurality of studs 18 to which are secured side boards 19 and 20 forming the side wall. The studs 18 are of greater length than the height of the side wall and have their excess length arranged at the lower end of the wall. The hinge bolts 16 pass through these studs and form a pivot for the side walls, the point of pivotal engagement being such that when the side walls are vertically disposed, the lower edge of the lowermost side wall board 20 lies immediately above the adjacent edge of the flooring 13 and when the studding and side walls are inclined but a very slight space is formed between the boards 20 and the adjacent edges of the flooring. When in an inclined position, the studs have their outer faces resting upon the sills 12 to be supported thereby and further have their beveled lower ends 21 engaged against the side faces of the adjacent sills 10 so that a two point support resisting the thrust of load against the inclined side walls is provided to remove strain from the hinge bolt 16.

A selected board, preferably the lowermost board 20 of the side wall, is made removable, being secured by bolts 22 and is of the same width as the distance between the edge of the flooring and the adjacent edge of the sill 16. The joists 11 are provided with bores 23 for the passage of bolts 22 so that the sides may be removed by removing the bolt 16, the boards 20 removed and placed upon the joists to fill the space 14 and bolted in position by the bolts employed for securing it to the sides. The rails 12 are preferably thicker than the material employed for flooring and siding so that they project thereabove and will prevent side shifting of loads arranged upon the flat body.

End gates 24 are provided, each having secured thereto, at each side thereof and adjacent their tops, pins 25 projecting at opposite sides of the end gate and adapted to engage in openings 26 formed in the box sides 17 when the box sides are moved to vertical position. Each end gate is further provided adjacent its lower end with a guide 27 having slidably mounted therein a retaining pin 28 adapted to engage in an opening 29 formed in the wagon bed. As a means for retaining the box sides in elevated position, bars are provided, as at 30, these bars being of a length to bridge the distance between

the side walls and having their end portions 31 adapted to engage the outer faces of the side walls and prevent separation thereof.

It will be obvious that a wagon or truck

5 box constructed in accordance with the foregoing may be readily and cheaply produced and will be durable and efficient in service. It will furthermore be obvious that the construction hereinbefore set forth is obviously capable of a certain range of change and modification without materially departing from the spirit of the invention and I accordingly do not limit myself to such specific structure except as hereinafter claimed.

10 15 I claim:—

1. In a wagon or truck body, transversely extending joists, flooring upon the joists of less width than the length of the joists, rails connecting corresponding ends of the joists

20 and box sides of greater width than the distance between either edge of the flooring and the adjacent rail, removably pivoted to the joists adjacent each edge of the flooring and swingable from a vertical position

25 where they combine with the flooring to provide the bottom and sides of a box to an inclined position where they rest upon and are supported by said rails, each box side including a wall element bodily removable

from the box side and of the same width 30 as the space between each edge of the flooring and the adjacent rail, the pivotal connections of the box sides being removable to permit removal of the sides.

2. In a wagon or truck body, transversely 35 extending joists, flooring upon the joists of less width than the length of the joists, rails connecting corresponding ends of the joists and spaced from the adjacent edges of the flooring, a removable longitudinally directed 40 pivot bolt extending through the joists at each edge of the flooring, box sides each including a wall structure and vertical studs connecting elements of the wall structure and projecting below the wall structure, each 45 of said studs having an opening for the passage of the corresponding pivot bolt intermediate the length of the projecting portion of the studs, the joists resting upon and being secured to longitudinally extending sills, 50 the lower ends of the studs being formed for engagement with adjacent faces of adjacent sills when the upper ends of the studs come into engagement with the rails.

55 In testimony whereof I hereunto affix my signature.

EARL R. BROWN.
